Term of patent 14 years

(Cl. D57—1)

FIG. -1-

FIG. 1 is a top plan view of a spectacle frame, showing my new design.

FIG. 2 is a front elevational view thereof.

FIG. 3 is a side elevational view thereof.

The dominant features of the design reside in the portion shown in full lines.

The temples are shown broken away in FIG. 1 for convenience of illustration. The side not shown is substantially a mirror image of the side shown.

I claim:

The ornamental design for a spectacle frame, substantially as shown and described.
